Des. 212,222

Patented Sept. 17, 1968

212,222

INSECT TRAP HOUSING

Oscar Miller, 4 Overlook Park,
Newton Center, Mass. 02159

Filed Mar. 28, 1968, Ser. No. 11,169

Term of patent 14 years

(Cl. D22—19)

FIG. 1

FIG. 2

FIG. 3

FIG. 4

FIG. 5

FIG. 1 is an elevation view of the insect trap housing;
FIG. 2 is an elevation view rotated 45° from the view
of FIG. 1;

FIG. 3 is a top plan view thereof;

FIG. 4 is a bottom plan view thereof; and

FIG. 5 is a cross sectional view taken along the section
line 1—1 in FIG. 1.

I claim:

The ornamental design for an insect trap housing, as
shown.
